ATTACHMENT FOR PIPE BITS

Frank H. Marland, New Bedford, Mass., assignor
of one-half to Robert F. Marland, North Dart-
mouth, Mass.

Application August 7, 1950, Serial No. 178,091

7 Claims. (Cl. 131—228)

1

This invention relates to new and useful improvements in pipe bits, stems or the like and the primary object of the present invention is to provide an attachment for a pipe bit that is sufficiently small to enter a user's mouth to engage behind the user's lower teeth or gum so that a pipe may be easily carried by a user having artificial teeth or insufficient teeth for supporting the pipe in a convenient manner.

Another important object of the present invention is to provide an attachment of the aforementioned character that is longitudinally adjustable upon a pipe stem or bit whereby the attachment may be placed to the comfort of the user.

A further object of the present invention is to provide an attachment for pipe stems, bits and the like composed of two adjustably connected ring forming members that are so constructed and joined as to permit the same to be applied to bits or stems of various widths.

A still further aim of the present invention is to provide an attachment for pipes that is simple and practical in construction, strong and reliable in use, small and compact in structure, inexpensive to manufacture, and otherwise well adapted for the purposes for which the same is intended.

Other objects and advantages reside in the details of construction and operation as more fully hereinlater described and claimed, reference being had to the accompanying drawings forming part hereof, wherein like numerals refer to like parts throughout, and in which:

Figure 1 is a perspective view of a pipe stem showing the invention applied to the bit;

Figure 2 is a perspective view of the present invention;

Figure 3 is a sectional view taken substantially on the plane of section line 3—3 of Figure 1;

Figure 4 is a plan view of the invention in modified form; and

Figure 5 is a longitudinal vertical sectional view taken substantially on the plane of section line 5—5 of Figure 4.

Referring now to the drawings in detail, wherein for the purpose of illustration, there is disclosed a preferred embodiment of the present invention, the numeral 10 represents a smoothly curved U-shaped or ring like member of any suitable material, such as hard rubber or plastic, having its ends turned inwardly to form retainer flanges 12 and 14.

The entire surface of the member 10, including the flanges 12 and 14, is smooth to prevent the device from scratching or harmfully affecting a

2

user's mouth, gum or teeth. The inner surface 16 of the member 10 is curved to conform to the lower surface S of a pipe stem or bit B and the inner faces 18 of the leg portions 20 of the member 10 are rounded to conform to the side edges E of the bit B. Further, the inner faces 22 of the flanges 12 and 14 conform to the curvature of the upper surface of the bit B.

The member 10 and flanges 12 and 14 are frictionally fitted on the bit B and the member 10 may be adjusted longitudinally upon the bit by manual force.

In practical use of the attachment, the same being applied to the bit, it is merely necessary for the bit and attachment to be inserted in a user's mouth to engage the member 10 behind the lower teeth or gum of the user in order to permit comfortable carrying or holding of the pipe P.

Reference is now made to Figures 4 and 5 wherein the invention is shown in slightly modified form. In this embodiment the ring like or U-shaped member 30 is composed of two hook shaped portions 32 and 34 having flanges 36 and 38.

The portions 32 and 34 are smoothly curved for the same purpose as the member 10 and the portions 32 and 34 are shaped to conform to and embrace a pipe bit. The adjacent thick ends 40 and 42 of the portions 32 and 34 are adjustably connected by a fastener 44 that extends through an opening 46 in the end 42 and which is threaded in a recess or aperture 48 in the end 40.

The opening 46 includes outwardly flared ends 50 and 52, one of which, 52, receives the head 54 of the fastener and the other of which permits rocking of the portion 34 when the fastener is loosened or backed up.

The member 30 is adapted for bits B of various widths due to the manner in which the portions 32 and 34 are adjustably connected. Further the member 30 is also longitudinally adjustable on the bit and may be readily applied to or removed from the bit by backing-up on the fastener and then rocking the portion 32 about and from the bit.

It is preferred that the portions 32 and 34 be formed with interconnecting means in the form of a tongue and groove, see Figure 4, so that these parts may be engaged when the member 30 is applied to bits that are relatively small in width.

In view of the foregoing description taken in conjunction with the accompanying drawings it is believed that a clear understanding of the construction, operation and advantages of the device will be quite apparent to those skilled in this art.

A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. An attachment for pipe bits comprising a rigid U-shaped member adapted to extend transversely of and embrace a bit and being sufficiently small to fit completely within a user's mouth and being disposed behind a user's lower gum, and inturned flanges on the limbs of said member for overlying a pipe bit, said member comprising separable halves, and a fastener adjustably connecting said halves.

2. For use with a pipe bit, a pair of complementary hook members adapted to embrace a pipe bit, one of said members having a threaded aperture and the other of said members having an opening in registry with said aperture, and a fastener extending through the opening and threaded in the aperture.

3. The combination of claim 2 wherein said opening includes outwardly flared ends, said fastener having a head seated in one end of said opening.

4. An attachment for pipe bits comprising a pair of complementary hook members each having an inner end and an outer end, said members being progressively reduced in cross-section from their inner ends towards their outer ends, said inner end of one member having a longitudinal opening therein and the inner end of the other member having a threaded aperture in registry with said opening, a headed fastener extending through the opening and threaded in the aperture, the inner end of one of said members having a groove therein extending across the opening and the aperture, and a rib on the inner end of the other

member adapted to enter the groove when the fastener is tightened to bring the inner end portions of the members together.

5. In a pipe bit, a member underlying the bit and having a concave surface held against the undersurface of the bit, said member extending transversely of the bit and having inturned end portions overlying the bit, said member being composed of two sections, and means adjustably connecting the sections and clamping the sections against the bit.

member adapted to enter the groove when the fastener is tightened to bring the inner end portions of the members together.

5. In a pipe bit, a member underlying the bit and having a concave surface held against the undersurface of the bit, said member extending transversely of the bit and having inturned end portions overlying the bit, said member being composed of two sections, and means adjustably connecting the sections against the bit.

6. A pipe bit attachment comprising a channel-shaped member having a base, side walls and inwardly facing flanges at the upper ends of the side walls, said flanges having their inner facing edges spaced apart, the channel-shaped member being of a shape corresponding substantially to the shape of the bit of a mouthpiece of a smoking pipe, said attachment when in position on the mouthpiece permitting a portion of a lip of a smoker to rest on the bit surface in the space between the flanges.

7. The combination of claim 6 wherein said base is composed of two sections and fastening means connecting said sections.
